(57) CLAIM

The ornamental design for a golf club head, as shown and described.

DESCRIPTION

FIG. 1 is a bottom plan view of a golf club head, showing our new design;

FIG. 2 is a top plan view thereof;

FIG. 3 is a front view thereof;

FIG. 4 is a back view thereof;

FIG. 5 is a left side view thereof;

FIG. 6 is a right side view thereof; and,

FIG. 7 is a sectional view thereof, taken along line 7-7 of FIG. 1.

The broken lines in the drawings illustrate portions of the golf club head that form no part of the claimed design.
